United States Patent

Des. 237,878
Patented Dec. 2, 1975

237,878

MULTI-METER EDUCATIONAL BOARD

Charles G. Valentine, Stamford, Conn., assignor to
Xerox Corporation, Stamford, Conn.

Filed Apr. 27, 1973, Ser. No. 355,140

Term of patent 14 years

Int. Cl. D19—07

U.S. Cl. D19—62

FIG. 2

FIG. 1 is a right perspective view of multi-meter educational board showing my new design; and

FIG. 2 is a left perspective view thereof.

The rear of the multi-meter educational board not shown is plain and unornamented.

I claim:

The ornamental design of a multi-meter educational board, substantially as shown and described.
